US00D827635S

(12) **United States Design Patent** (10) Patent No.: **US D827,635 S**
(45) Date of Patent: ** Sep. 4, 2018

(54) **GRAPHIC TABLET**

(71) Applicant: **Luo Wei**, Guangdong (CN)
(72) Inventor: **Luo Wei**, Guangdong (CN)
(73) Assignee: **SHENZHEN HUION ANIMATION TECHNOLOGY CO. LTD.**, Shenzhen, Guangdong (CN)

(**) Term: **15 Years**

(21) Appl. No.: **29/586,773**

(22) Filed: **Dec. 7, 2016**

(51) LOC (11) Cl. **14-02**
(52) U.S. Cl.
USPC **D14/341**

(58) **Field of Classification Search**

(57) **CLAIM**

The ornamental design for a graphic tablet, as shown and described.

DESCRIPTION

FIG. 1 is a front, bottom right perspective view for a graphic tablet, showing my new design;

FIG. 2 is another perspective view thereof;

FIG. 3 is a front elevational view thereof;

FIG. 4 is a rear elevational view thereof;

FIG. 5 is a top plan view thereof;

FIG. 6 is a bottom plan elevational view thereof;

FIG. 7 is a right side elevational view thereof; and,

FIG. 8 is a left side elevational view thereof.

The broken lines in the figures depict portions of the graphic tablet that form no part of the claimed design.

1 Claim, 6 Drawing Sheets
